(57) **CLAIM**

The ornamental design for a laundry ball, as shown and described.

DESCRIPTION

FIG. 1 is a perspective view of a laundry ball showing our new design.

FIG. 2 is a front elevational view thereof.

FIG. 3 is a top plan view thereof; and,

FIG. 4 is a bottom plan view thereof.

A rear elevational view, a left-side elevational view and a right-side elevation view of the laundry ball are omitted because they are the same as the front elevational view thereof.
